UNITED STATES PATENT OFFICE.

CHARLES WHITNEY MORDEN, OF WEST LINN, OREGON.

SLICE FOR PAPER-MAKING MACHINES.

Application filed June 6, 1923. Serial No. 643,794.

To all whom it may concern:

Be it known that I, CHARLES W. MORDEN, a citizen of the United States, and resident of West Linn, county of Clackamas, State 5 of Oregon, have invented a certain new and useful Improvement in Slices for Paper-Making Machines, of which the following is a specification.

My invention relates to paper making machines and more particularly to the slice 10 which regulates the flow of paper stock on to the paper machine wire.

Heretofore slices have generally been made of sections which are overlapped at 15 their jointures. The major vertical adjustments have been made at the ends of the slice and the minor, closer, adjustments have been made at the jointures by moving the plates relatively to each other.

One of the main objects of my invention 20 is to provide a suitable slice composed of a main member or part which has one or more complementary pieces bolted thereto. The slice so provided is supported at its 25 ends by the deckle frame and has a flexible bar constituting a lip mounted on its lower edge which preferably is also made in sections corresponding in length with said part and complementary piece. I also provide 30 means for flexing the bar relatively to the apron board so as to neutralize uneven strata in the flow of the stock and thus cause such flow to become uniform throughout its width.

A further object is to provide a slice 35 which is made up of a plurality of pieces which are rigidly bolted together, with the ends of the adjoining pieces overlapping each other. Thus I provide an efficient slice 40 capable of being arranged to run different widths of paper.

I attain my object in a paper making machine having two deckle frames spaced apart, relatively adjustable towards and 45 from each other, and a slice supported between them, said slice consisting of a main part of lesser length than the space between said deckle frames in one of their adjustments, a removable complementary filling 50 piece carried by one end of said main part to make the length of the slice correspond with said space, a flexible lip adjustably secured to the lower edges of said main part of the slice and said complementary piece. 55 I also preferably provide on that end of the slice to which said complementary piece

is affixed, an arm of substantial width, thereby firmly holding the slice in vertical alinement, such arm extending across the complementary piece to the adjacent deckle frame. I also preferably make the flexible lip in sections which correspond in length with the respective lengths of the main part and said complementary piece.

The construction and operation of my improved slice I have illustrated in the accompanying drawings in which:

Fig. 1 is a plan view of my improved slice mounted in position between two deckle frames.

Fig. 2 is an elevation of my improved slice with one type of flexible lip mounted on its lower edge, the deckle frames and deckle straps being shown in section.

Fig. 2^a is a fragmentary elevation of and 75 Fig. 2^b is a vertical section through a slice embodying my invention which has a different type of flexible lip, these views being merely diagrammatic.

Fig. 3 is a fragmentary view of one end 80 of my improved slice taken approximately on a line of 3-3 of Fig. 5 and shows how my improved slice is horizontally and vertically adjustable and supported by the deckle frames.

Fig. 4 is a fragmentary plan view of one end of my improved slice in place and shows a portion of a deckle frame.

Fig. 5 is a fragmentary side elevation of 90 a deckle frame and the adjacent end of the slice, said view being taken in the direction of the arrows in Fig. 3, and shows the mechanism by which my improved slice is adjustably supported in the deckle frames.

Fig. 6 is a section taken on the line 6-6 95 of Fig. 3.

Fig. 7 is a section taken on the line 7-7 100 of Fig. 3 which is through the jointure between the main portion of the slice and the complementary section.

Fig. 8 is a section taken on the line 8-8 105 of Fig. 3 which is through one of the adjusting rods for the flexible lip.

Fig. 9 shows complementary fragmentary perspective views of one end of the main part of the slice, of the related complementary piece, and of the related sections of the flexible lip which are mounted on the bottom edges of the said slice parts.

My improved slice is mounted transversely across a paper machine, a part of which is shown as 1, between the two deckle frames.

2. It is mounted over the apron board 3 and is vertically adjustable in the deckle frames so that the space 4^a between the apron board and the edge of the slice provides an aperture through which stock can flow.

As is common, a quantity of paper stock is held in a head box 4, the slice and the two deckle frame side plates 2^a constituting 10 three sides of the box. It is necessary therefore that the slice fit snugly against the deckle frames so as to prevent leakage between the deckle frames and the ends of the slice. Leakage would spoil the formation of 15 the paper stock flowing through the aperture 4^a between the slice and the apron board 3.

Paper machines are made so that the 20 deckle frames may be adjusted inwardly and outwardly so as to vary the width of the sheet of paper formed by said paper making machine. The slice necessarily must fit snugly against the deckle frames, and thus means must be provided to correspondingly 25 vary the length of the slice so as to accommodate said movement inwardly and outwardly of the side frames.

In my improved slice I have provided a 30 one piece slice 5 which is as long as the narrowest adjustment of the side frames. Offset supports 6, mounted in boxings 7 in the deckle frames, adjustably support said slice across the paper machine. When it is 35 desired to make wider sheets of paper, complementary pieces 5^a may be used to fill out the space between the end of the slice 5 and the adjacent deckle frame 2. The joint between the complementary piece 5^a and the main section of the slice 5 is preferably 40 stepped or overlapping as at 8, so as to prevent stock in the head box from passing readily through this jointure. The complementary piece is fastened securely to the main piece of the slice 5 by screws which 45 may be passed through the holes 9. Guide lugs 10 on the complementary piece, interlock with complementary blocks 11 on the deckle frames and cooperate with the supporting boxings 7, to hold the slice in vertical alinement. The offset supporting portion 6 at each end of the slice, is fastened 50 to the main member 5 of the slice by means of bolts 12 and is mounted so as to have horizontal adjustment in the boxings 7, said 55 boxings 7 are vertically adjustable and are held in vertical alinement by guiding lips 7^a fastened to the deckle frames. Each of the boxings 7 has an integral threaded rod 13 mounted in the adjusting nuts 14 by which 60 the boxing and therefore the slice can be adjusted vertically. The adjusting nuts 14 are supported between two ears 15 on the side frames, which prevent any play in the adjusting means. It is to be noticed that 65 the complementary pieces 5^a are firmly fas-

tened to the main body of the slice 5 so that said connected parts function as an integral slice, but none of the weight of the main member is carried by the complementary members. The complementary pieces are 70 carried by the main member and the interlocking guides 10 and 11 hold the entire slice in vertical alinement. The slice is relatively inflexible and thus is not bowed by its weight. The bottom edge of the slice will 75 thus be substantially horizontal at all times. A longitudinal rib 16 at the top serves as a stiffening rib preventing the slice from being bowed. One type of auxiliary adjusting means especially adapted for use with this 80 type of slice is the adjustable flexible bar 17 which is carried by the lower edge 24 of my improved slice. The lower edge of the slice is substantially uniform throughout its 85 length and a groove 25 is provided in the adjustable bar which is substantially the same width as the lower edge of the slice and the opposed walls of the groove thus, have close contact with the sides of the bottom edge of the slice and thus prevent stock 90 from passing through the jointure. Said groove is also of substantial depth and thus when the lip is moved relatively to the slice 95 the seal is retained because of this close fit and thus stock is prevented from passing through the jointure even though the bottom edge of the slice does not seat on the bottom edge of the groove. Means are provided for adjusting the bar relatively to the 100 slice. These consist of a plurality of spaced rods 18 the lower ends of which are seated in the bar as at 18^a. The upper end of each of the rods is threaded in the elongated shank 19 of a handwheel 23, which 105 fits in the recess 20 of the longitudinal rib 16. Said shank is held in position in the recess by a removable plate 21 which is fastened to the longitudinal rib by screws 22. Each hand wheel 23 theraded on the end of 110 each rod 18 bears against the longitudinal rib 16 and thus the portion of the bar 18 in which it is seated can be moved and held in any set position. Said rods are spaced along the slice and the minor vertical adjustments of the slice can be taken care of. 115 The hand wheels 23 can be locked in set position by means of a lock nut 26. Removable pieces 27 can be fastened to the main bar 17 as shown in Fig. 3. These 120 pieces correspond in length to the width of the complementary pieces 5^a used. The bars 17 and 27 have cooperating flanges 28 which may be held together by bolts 29 and thus make the bar sections substantially continuous and rigid and independent of the slice 125 portions 5 and 5^a.

In Figs. 2^a and 2^b I show a slightly different type of flexible lip 30 which is adaptable for use with my improved slice. This flexible lip 30 is made of a relatively 130

thin piece of flexible material which is fastened to the bottom of the main portion of the slice as at 24* and is inclined toward the apron board in the direction of the flow of 5 the paper stock and thus forms an orifice with a stream like contour. I provide similar adjusting mechanism for this lip as is shown for adjusting the lip 17. Such mechanism consists of hand wheels 26 10 which moves rods 18 longitudinally and thus flex the lip upwardly and downwardly. Raising the lip causes a wider orifice 31 to be formed between the edge of the lip 30* and the apron board 3.

15 I also provide removable sections 32 for this type of flexible lip. These sections are held to the main portion of the lip 30 similar to the manner in which the removable section 27 is affixed to the main portion of 20 the lip 17, which is by companion flanges as 33 which are bolted together and thus the complementary section forms an extension of the main section.

I claim:

25 1. In a paper making machine, in combination with two deckle frames spaced apart, relatively adjustable towards and from each other, and a slice supported between them, said slice consisting of a main 30 part of lesser length than the space between said deckle frames in one of their adjustments, a removable complementary filling piece carried by one end of said main part to make the length of the slice correspond 35 with said space, that end of the slice to which said complementary piece is affixed being provided at approximately its middle with an arm extending across the complementary piece to the adjacent deckle frame 40 and constituting an element for supporting such end of the slice by that deckle frame.

2. In a paper making machine, in combination with two deckle frames spaced apart, relatively adjustable towards and 45 from each other, and a slice supported between them, said slice consisting of a main part of lesser length than the space between said deckle frames in one of their adjustments, a removable complementary filling 50 piece carried by one end of said main part to make the length of the slice correspond with said space, that end of the slice to which said complementary piece is affixed being provided with an arm of substantial 55 width, thereby firmly holding the slice in

vertical alinement, such arm extending across the complementary piece to the adjacent deckle frame.

3. In a paper making machine, in combination with two deckle frames spaced apart, relatively adjustable towards and from each other, and a slice supported between them, said slice consisting of a main part of lesser length than the space between said deckle frames in one of their adjustments, 60 a removable complementary filling piece carried by one end of said main part to make the length of the slice correspond with said piece, a flexible lip adjustably secured to the lower edges of said main part 65 of the slice and said complementary piece.

4. In a paper machine, in combination with two deckle frames spaced apart, relatively adjustable towards and from each other, and a slice supported between them, 70 said slice consisting of a main part of lesser length than the space between said deckle frames in one of their adjustments, a removable complementary filling piece carried by one end of said main part to make the 75 length of the slice correspond with said piece, a flexible lip adjustably secured to the lower edges of said main part of the slice and said complementary piece, said lip being made in sections corresponding in length 80 with the respective length of said main body and said complementary piece.

5. In a paper making machine, in combination with two deckle frames spaced apart, relatively adjustable towards and from each other, and a slice supported between them, 85 said slice consisting of a main part of lesser length than the space between said deckle frames in one of their adjustments, a removable complementary filling piece carried by one end of said main part to make the length of the slice correspond with said space, the joined ends of said main part of the slice and said complementary filling 90 piece having overlapping lips, the bottom end of said slice in its entirety being of uniform thickness throughout its length and a flexible lip secured to the said bottom end, said lip being provided with a groove of uniform cross sectional area corresponding 100 to said thickness so that the said bottom edge of the slice in its entirety will fill said groove.

CHARLES WHITNEY MORDEN.
